UNITED STATES PATENT OFFICE.

GEORGE MCCREARY PINKERTON, OF YORK, PENNSYLVANIA.

MACHINE FOR MOLDING AND CUTTING ICE-CREAM.

SPECIFICATION forming part of Letters Patent No. 656,044, dated August 14, 1900.

Application filed March 22, 1900. Serial No. 9,764. (No model.)

To all whom it may concern:

Be it known that I, GEORGE MCCREARY PINKERTON, residing at York, in the county of York and State of Pennsylvania, have invented certain new and useful Improvements in Machines for Molding and Cutting Ice-Cream, of which the following is a specification.

This invention has for its object a machine for molding and cutting ice-cream, of a very simple and economical construction, which can be easily manipulated and which will effectively serve for its intended purposes.

The invention consists in the novel features of construction and combination of parts, which I shall now proceed to describe and claim, reference being had to the accompanying drawings, in which—

Figure 1 is a front perspective view of the improvement. Fig. 2 is a longitudinal section of the front or cutter end. Fig. 3 is a detail view of the pawl devices hereinafter referred to, and Fig. 4 is a detail view of the means for tilting the slicer-knife.

My improvement comprises a suitable frame having a longitudinal bed portion 1, on the front end of which is mounted a suitable vertical frame 2, in which the mold is adapted to be secured.

3 3 indicate two guide-rods in front vertically movable on the frame 2, to which is secured a cross wire or blade knife 4, adjusted by means of tension-bolts 5.

6 6 indicate a pair of guide-posts fixedly held between the guide-rods 3 3, on which is supported a slicing-knife 7, having a rocker-bearing, one end thereof connecting with a crank 7^a, said knife being adapted to tilt the cream off onto the wrappers 8, disposed on the table 9 in front of the discharge end of the machine, as clearly shown in Fig. 1. After having been tilted the slicer-knife is returned to its normal (slicing) position by means of a stay 11 and the coiled spring 12, which draws it against the stay.

45 The guide-rods 3 3 have a cross-head 3^a at the top, centrally of which projects a vertical guide or extension 10, having a fixed inwardly-projecting lug 10^a at the top and an adjustable lug 10^b at the bottom. The lower 50 ends of the vertically-sliding guide-rods 3 3 have a cross-bar 3^b, with which connects a pendent pitman-rod 3^c, pivotally connected

at the lower end to a treadle 13 in such manner that when the same is depressed the slide-rods and their attached cutting-knife will be moved upward into a position to sever the cream-body into its proper length.

In order to automatically tilt the slicer-knife 7, I pivotally mount on a short post adjacent the crank 7^a a trip-lever 7^b, whose weight is so disposed that its forward arm will normally rest loosely on the crank 7^a and whose rear arm is in the path of one of the tension-bolts 5. Thus it will be seen that when the guide-rods 3 3 move upwardly a bolt 5 will strike against the trip-lever 7^b and cause it to depress the crank 7^a and tilt the slicer-knife 7, the latter being returned to normal position by the spring 12, as described above.

70 In connection with the cutting and slicing means I employ automatically-operated devices for feeding the cream-block forward. In the drawings I have shown the front frame provided with a bifurcated standard 14^b, in which is journaled a bell-crank lever, the long arm 14 of which projects in the path of the lugs 10^a 10^b of the sliding frame, while its short arm connects with a pitman 14^a to operate the feed-pawls, presently more fully described. In practice the lower lug 10^b engages the lever-arm 14 when the cutter-knife is above the mold and rocks the lever to effect a feed movement to push the frozen cream-block forward the desired distance. 85 When pressure on treadle is removed, the guide-rods drop, the knife cutting the cream at such movement, and during this movement the upper lug 10^a engages the lever-arm 14 and draws the shifting-pawls back to their 90 rearward (normal) position.

16 indicates the feed or shifting pawls, of which I preferably employ five and which are held for longitudinal play, they having slide-block bearings 16^a, which are adapted to be moved back and forth between the set-screws 19^a on the cross-head guide 19, such pawls in practice having their outer ends terminating in quarter-inch rack-engaging teeth. By adjusting the set-screws 19^a, and consequently the movement of the bearing-blocks, the thickness of the block to be cut is regulated.

100 20 indicates a combined rack and plunger,

one end of which enters the mold fixedly held at the front end and to which is bolted a wooden block 21, which fits the said mold. The plunger slides on the parallel guide-
5 plates 22, secured to the bed-plate 1, and the cross-head guide is also bolted to the said bed-plate 1.

From the foregoing description it will be observed that I have provided a very simple 10 and effective means for molding and cutting ice-cream in small blocks to be wrapped in paper, said machine being of such a nature that the blocks can be so quickly and economically cut and wrapped that they can be 15 sold at a very small cost.

It will be understood that by providing a plurality of fixedly-held knives at the front the frozen block can be cut into a number 20 of cakes at each operation of the cutting-knife.

Having thus described my invention, what I claim as new, and desire to secure by Letters Patent, is—

1. In a machine for the purpose specified, 25 the combination with a longitudinal bed, a mold, and a slidable plunger, of the vertical parallel guide-rods, 3, 4, a transverse blade connecting the latter, a cross-head arranged on and connecting the upper ends of said 30 guide-rods, a vertical extension of said cross-bar, automatically-operated means connecting such extension with the plunger, and a treadle for reciprocating the aforesaid guide-rods, substantially as shown and described.

35 2. In a machine as described, a stationary slicer-knife having a tilting movement, means for automatically tilting said knife and means for returning it to its normal or slicing position, substantially as shown and described.

40 3. In a machine as described, a plunger, a bell-crank lever, longitudinally-movable pawls for shifting the plunger forward, the pitman connecting the bell-crank lever and such pawls, and means for manipulating the 45 bell-crank lever, as set forth.

4. A machine for cutting ice-cream, comprising a suitable framework, a tilting slicer-knife, a reciprocating guide-frame a cutting-knife carried thereby, a plunger mechanism, feed-pawls for forcing it intermittently

forward and a mechanism for operating said pawls connected with the reciprocating guide-frame as set forth.

5. In a machine of the character described, 55 the combination of a vertically-reciprocating cutting-knife, a tilting slicer-knife, means for operating said cutting-knife, and a trip for tilting said slicer-knife, said trip being actuated by the operating means for the cutting-knife, as set forth.

6. In a machine of the character described, 60 a reciprocating cutter-knife, guide-rods carrying said knife, a tilting slicer-knife provided with a crank, and a trip-lever adapted to depress said crank and arranged for engagement by a device carried by one of said guide-rods, as set forth.

7. In a device of the character described, 70 a reciprocating cutting-knife, guide-rods carrying said knife, a tilting slicer-knife having a crank, a trip-lever adapted to move said crank and arranged to be tripped by the movement of the guide-rods, and spring secured to said crank whereby to return the slicer-knife to its normal position, as set forth.

75 8. In a machine of the character described, a mold-box, a cutting-knife movable across said mold-box, guide-rods carrying said knife and having an extension formed with lugs, a bell-crank lever one arm of which is located 80 in the path of said lugs, pawls adapted to feed the material into the mold-box, and a pitman connecting said pawls with the other arm of said lever, as set forth.

9. In a machine of the character described, 85 a mold-box, a plunger and rack-bar adapted to feed the material into said mold-box, pawls arranged for engagement with the rack-bar to feed the same forward, bearing-blocks on which said pawls are mounted, guides in which 90 said blocks are slidably fitted, and means in said guides for regulating the movement of said blocks, as set forth.

In testimony whereof I have signed my name to this specification in the presence of 95 two subscribing witnesses.

GEORGE McCREARY PINKERTON.
